MACHINE FOR OPERATING UPON SHOE-HEELS

Charles G. Brostrom, Peabody, Mass., assignor to
 United Shoe Machinery Corporation, Paterson, N. J., a corporation of New Jersey

Application May 25, 1934, Serial No. 727,509

171 Claims.

(Cl. 12—77)

My invention relates to means for performing operations upon the heels of shoes, being more particularly concerned with the finishing or burnishing of the curved peripheral portion, as that 5 of the top-lifts of heels before their attachment to the shoes. It is an object of the invention to perform the finishing or other operation automatically at a relatively high rate and with the production of uniform results.

10 In the attainment of this object, I utilize, as a feature of the invention, a movable tool which may be rotated or oscillated and which, in the present instance, is a burnishing tool. About this tool the heels to be operated upon are carried by holders, there being preferably a plurality of these holders upon the heels in which the tool acts simultaneously. This plurality of holders may be mounted upon a rotatable turret. As 15 herein disclosed, the movement of the holders 20 is one of revolution about both the axis of the tool and of the turret, the holder or holders rotating also about the longitudinal axes of the heels they contain. By producing these movements at the proper relative speeds and uniformly, all portions 25 of the peripheral surface of each heel to be operated upon may be subjected to the action of the tool for the same length of time, the work being completed during the travel of the holder once about said tool. Moreover, the holders may 30 be maintained in the same angular relation about their axes during this revolution. This facilitates the application or loading of the heels, since a breast-bar or other gage upon each holder will be kept in a chosen relation to the loading position. 35 With plural holders, the tool will be caused to act simultaneously upon all the contained heels, these being applied and removed successively as the holder passes through a limited arc of their travel at the loading position. At this position 40 there may be means for facilitating the loading of the holders and means for ejecting the finished heels. To insure continuous contact with the tool of the curved surfaces operated upon, the holders may be moved bodily with respect to the tool, 45 as by being mounted upon individually movable carriages normally urged toward the tool, this being conveniently effected by springs. Control is exercised over this bodily movement of the holders, as by a cam or cams, and at certain periods 50 during their travel the holders will be removed from the tool to give opportunity for loading and unloading. At this time, elements of the holders which clamp the heels may be caused to separate 55 automatically and again approach each other to

produce their clamping effect. Movement of a holder into co-operation with the tool when no heel has been applied, with possible resulting damage, is prevented by locking means released only by the presence of a heel in clamped relation. 5

Other features of the invention involve the structure of the heel-holders, the manner in which they position and retain the heels, their action in clamping and unclamping said heels, 10 and their rotation upon their supporting carriages; the means for moving the carriages and for controlling this motion, including a locking device for each carriage; a support under the guidance of which the heels may conveniently be 15 inserted by the operator between the clamping members of the holders, a machine-driven element being disclosed as a possible part of this loading arrangement; the establishment of a proper loading relation between the support and 20 the holders; the ejection of the finished heels from the holders; the structure of the burnishing tool and the manner of its adjustment, both bodily and sectionally, and of applying heat to 25 it; the gaging or positioning of portions of the heel-holders; and interchangeable connections whereby the tool may be either rotated or oscillated. 30

In the accompanying drawings, a particular embodiment of the invention is illustrated, 30

Fig. 1 being a front elevation of my improved machine, with parts broken away;

Fig. 2, a similar view in side elevation, looking from the left in Fig. 1;

Fig. 3, a broken top-plan view;

Fig. 4, an enlarged horizontal section on the line IV—IV of Fig. 2, parts being omitted;

Fig. 5, an enlarged elevation, partly in section, of the upper portion of the machine;

Fig. 6, an enlarged sectional detail on the line VI—VI of Fig. 5;

Fig. 7, an enlarged vertical section through the shafts of the turret and burnishing tool and through associated adjusting means;

Fig. 8, a similar view through half the burnishing tool and its immediately associated adjusting elements;

Fig. 9, a detail in front elevation of the cams for controlling the work-holding carriages;

Fig. 10, a perspective view of the elements controlling the work-clamping means, the parts being shown as separated;

Fig. 11, a like view of a turret-actuated loading device for the heel-holders;

Fig. 12, a detail in perspective of a portion of said device; while

Fig. 13 shows in perspective a driving connection for producing oscillatory movement of the burnishing tool.

The apparatus has a frame 20 furnishing both a support for the active elements and an enclosure for the major portion of those, other than the ones to which direct access by the operator is desired. The principal mechanisms A and B are respectively that by which the heels or other work-pieces are held for the operation upon them, and the means, more essentially a movable tool b, which performs such operation.

Considering first the work-presenting mechanism A, there is journaled vertically in the frame a tubular shaft 22 having fast upon its upper extremity a horizontal spider 24 furnishing the major element of a turret. This spider is shown as divided into four equal sections between which are spaces having at each side parallel ways for the guidance radially of the turret of a carriage 26, which may have anti-friction rolls 27 (Fig. 6) for contact with the opposite sides of the spider-arms. Each of the four carriages has mounted upon it the lower portion of a clamp which will hold a heel H with an attached top-lift T for presentation to the tool b. Secured in an upright position in the carriage is a sleeve 28 (Fig. 5), and rotatable in this sleeve is a spindle 30. The spindle is bored to receive a plunger 32 yieldable downwardly against the resistance of a relatively heavy spring 34 contained in the bore. Said plunger is compelled to rotate with the spindle by a slot-and-pin connection 36 and has secured to its upper end a double prong 38 arranged for engagement with the heel-seat-end of the heel. Keyed to the spindle 30 to rotate therewith is a sleeve 40. The adjacent ends of the sleeves 28 and 40 support or are provided with contacting cam-surfaces 42, both of which surround the axis of rotation of the spindle and are best shown in Fig. 10. The purpose of these cams will be later explained. Surrounding the upper portions of the spindle 30 and sleeve 40 is a carrier-sleeve 44, yieldable downwardly against a spring 46 interposed between it and the sleeve 40 and rotated with said sleeve by a slot-and-pin connection 48. The carrier-sleeve, at all times turning with the spindle, is to be considered a portion thereof. Trunnioned at 50 upon the carrier-sleeve is a work-clamping table 52. The heel-seat-end of the heel rests upon this table, the pivotal mounting allowing it to accommodate itself to heels of different pitches. Depending from one side of the table is a fork 54, and arranged to turn about the adjacent trunnion of the table is an arm 56 provided with a portion extending between the branches of the fork. The arm may be fixed in different angular positions, to correspond to the pitch of the heel being operated upon, by the engagement of a spring-actuated detent 58 which it carries with a toothed segment 60 (Fig. 5) attached to the carrier-sleeve 44. Between the arm 56 and the fork is a torsion-spring 62 which tends to turn the table clockwise. The movement of the table in either direction upon its pivotal mounting is limited by the contact of the fork with the arm. The heel may be correctly located upon the table by a breast-gage, in the form of a bar 64 extending across one side of said table, and by opposite side-gages, shown as arms 66, 66 pivoted upon the table. These arms are geared at 68 to turn together, a spring 70 (Fig. 3) holding them normally toward each other. The breast-bar and side-arms are preferably mounted

upon a slide 72 movable transversely of the table and furnishing a portion of its supporting surface. The slide is secured in position by a cam-lever 74. This provides for the positioning of these gaging members to correspond to the varying relation between the heel-seat-ends of heels of different types and their tread-surfaces. The prongs 38 of the plunger 32 project upwardly through an opening in the center of the table 52 to such an extent that they will engage a heel 10 applied to said table.

Each heel-clamping means may be completed by an upper contact member or pad 80 arranged for engagement with the top-lift of the heel. At each side of the table 52 a rod or upright 82 rises from the corresponding carriage 26, the upper extremities of each pair of rods being tied together by a bar 84. Guided upon these rods is a bar or slide 86, the central portion of which is yoked vertically at 88. The lower half of the yoke 86 carries the pad 80, backed by an anti-friction bearing 83 to permit free rotation. The upper portion of the yoke has connected to turn in it a screw 90 threaded through the bar 84. By turning the screw by its hand-wheel 92, the pad 80 may be adjusted vertically to bring it to the proper relation to the table 52 for heels of different heights. It may be locked in this adjusted position by a divided portion 94 of the bar 84, this divided portion being clamped upon the screw 90 by a screw 96 turned by a hand-wheel 98.

The four tables 52 with their pads 80 are revolved by the turret 24 about the tool b, so the operating point is gradually shifted about said tool. At the same time, each of these work-clamping holders is rotated about a vertical axis, so the point of operation is correspondingly moved about the periphery of the top-lift. The movements of revolution and rotation are in the directions indicated by the arrows in Fig. 4 and are provided by the following actuating mechanism: The shaft 22 of the turret 24 is rotated to revolve the holders from a main driving shaft 100 (Figs. 1 and 2). This shaft 100 is journaled horizontally at the bottom of the frame and receives power through a belt from a source not illustrated, said belt operating over fast and loose pulleys 102. Application of power to the shaft 100 is controlled by a belt-shifter 104 movable along a support 106 by a chain of elements consisting of a link 108, a crank 110 and a bevel-pinion 112 upon a shaft 114, and a bevel-segment 116 and hand-crank 118 upon a shaft 120 extending from the rear to the front of the machine. Fixed upon the shaft 100 is a worm 122, with which meshes a worm-wheel 124 upon a short vertical shaft 126 journaled upon the frame parallel to the shaft 22. Alined with the shaft 126 and rotatable in the frame is an intermediate shaft 128 joined by spur-gearing 130 to the shaft 22. Surrounding the shaft 128 is a tubular shaft 132 which is geared at 134 to a vertical shaft 136. This, in turn, is connected by worm-gearing 138 to a horizontal shaft 140 extending to the front of the machine, where it carries a hand-crank 141 for rotation by the operator. At the upper portion of the shaft 126 and the lower portion of the shaft 132 are the opposite members 142, 142 of a double jaw-clutch. An intermediate clutch member 144 is splined to the shaft 128. The member 144 has acting upon it a shifting yoke 146 held down by a spring 148 surrounding a depending rod 150. The lower end of the rod rests upon the rear of a treadle-lever 152. It will be seen that nor-

5 mally the clutch member 144 occupies its lowest position, connecting the shaft 128 with the shaft 126 so the turret will be rotated under power. If the operator wishes to turn the turret slowly, as for the purpose of making adjustments, the treadle 152 is depressed and may be temporarily locked down by a latch 154 pivoted above it upon the frame. The rear of the treadle lifts the rod 150 to cause the engagement of the upper half 10 of the clutch. The turret-shaft is thus disconnected from the power-shaft and is joined to the shaft 132 to receive rotation, as slowly as the operator may desire, from the crank 141. When the machine is ready for normal power-oper- 15 ation, the latch 154 is released, so the treadle is free to allow the engagement of the lower portion of the clutch.

20 To rotate the heel-holders upon the turret as they are revolved thereby about its axis, each spindle 30 is united by a universal joint 160 (Fig. 7), a telescopic shaft 162, and a second universal joint 164 to a short shaft 166 journaled in a disk 168 secured to the shaft 22 with the spider 24 and forming a part of the turret. Vertical rods 169 may join the disk and spider to each other. At the under side of the disk a gear 170 is keyed upon each shaft 166 and meshes with an idle pinion 172 rotatable about a stud 174 fixed in the disk. This pinion engages a gear 30 176 fast upon the frame and common to all the heel-holders. As the turret rotates and the heel-holders revolve about the tool *b*, the planetary gearing just described causes each holder to turn about a vertical axis passing through the heel 35 which it carries. The gearing is preferably so designed that, for each revolution of the holder by the turret, it will be once rotated upon said turret and at a uniform speed. Consequently, each heel introduced into one of the holders at 40 a loading position, before it again reaches such position, will have had the entire periphery of the top-lift of a heel clamped in it presented to be operated upon, and at a uniform rate. The described movement of the holders will cause 45 them to be kept throughout their travel in the same angular relation about their vertical axes, when referred to a stationary line, as that along which heels are supplied. That is, the breast-bars 64, for example, will always be parallel to the front of the machine. This facilitates the 50 introduction of the heels into the holders. The presentation of the heels to the tool is modified as will be hereinafter developed.

55 During the presentation of each heel, its top-lift may be held in operating engagement with the tool *b* by movement of the carriage 26 upon which the holder is supported. Formed upon the carriage outside the heel-holder is a casing 180 (Fig. 5), at the center of which a vertical spindle 182 is arranged to turn. Normally this movement is prevented by a detent 184 pivoted upon the slide and engaging a ratchet-wheel 186 secured to the spindle. Turning about the spindle is a pinion 188 meshing with a rack 190 (Fig. 7) attached to the spider 24. Connecting 60 an enlargement upon the hub of the pinion to the spindle is a spiral spring 192. The force applied by the spring to the pinion, and by said pinion through the rack to the turret, is such as to exert a constant tendency to carry the heel-holder 65 toward the tool, except when otherwise controlled, to hold against the tool the periphery of the top-lift of the heel clamped in the holder. The maximum extent of movement may be determined by a set-screw 194 threaded into the 70

spider between the carriage-ways. The force of the spring may be varied by rotating the spindle 182 to different angular positions, it being retained by the detent 184. If desired, auxiliary helical springs 195 (Fig. 3) joining the carriage 5 at its opposite sides to the spider may be utilized to increase the force with which the top-lift edge is urged against the tool. To alter the tension of the springs, their outer ends may be connected to studs 196 attached to the carriages 10 by conventional slot-and-screw connections 197. Obviously, either type of spring and adjustment may be employed alone, if the forces created are sufficient.

15 By the present machine, the tool *b* is to be caused to act only upon the curved periphery of the top-lift and not at the breast of a heel. Moreover, to avoid interference, each holder should be removed from the tool upon the entrance of said holder to the unloading and loading positions. To cause the spring mechanism to move each carriage inwardly only when the rotation of the heel-holder places the top-lift in the proper angular relation to the tool, and to move the carriage away from the tool for the 20 discharge of a finished heel and to allow the operator to apply another heel to the holder, I have provided controlling means which removes each carriage from its active position through a 25 definite angle in the rotation of the turret. This 30 is preferably for that portion of the revolution or bodily movement of the carriage during which the breast of the top-lift is being turned by the holder toward the tool. This not only limits the action of said tool to the desired portion of the 35 top-lift, but also gives time for the insertion by the operator of a heel in the holder and the ejection of the heel after the burnishing of its top-lift. Considering particularly Figs. 4 and 9, 40 sliding in segmental guides 200 below the spider 45 24 are carriage-controlling members having segmental shanks 201, movable in the guides and with cam-portions 204 overlapping each other and lying in planes above the shanks. An additional guiding effect may be furnished by studs 50 fixed in the frame and having portions 202 lying in arcuate slots 203 in the cam members. Each carriage 26 has depending from its outer extremity a roll 206 (Fig. 5), and when this roll is in contact with arcuate edges 208 of the cams, the carriage is drawn out against the force of its 55 springs 192 and 196, with the top-lift of the heel in its holder removed from the tool *b*. At this time a heel may be inserted in the holder, following the ejection of the heel previously operated upon. At 210 an inwardly inclined surface of one of the cams permits the springs to carry the holder into the operating position, just as the breast-corner is brought by the rotation of the holder into position for contact with the tool. 60 When the roll 206, in the operating travel of the holder, reaches the opposite extremity of the cam, it engages an outwardly inclined surface 212 of the second cam, which leads to the overlapping arcuate surfaces 208 concentric with the axis of 65 the turret. This removes the top-lift from the tool, placing the heel in position for ejection. The time of removal of the holders from and their return to the active operating position may be altered by changing the relation of the cam-surfaces 210 and 212 circumferentially of the 70 turret, this being accomplished by sliding them simultaneously in their guides. For this purpose each shank 201 bears upon its outer edge a rack 75 214, and with this meshes a pinion 216 fast upon

the upper extremity of a short vertical shaft 218. Bevel-gearing 220 joins each of the shafts 218 to one of two horizontal side-shafts 222 connected to an intermediate shaft 224 through bevel-gearing 226. One of the shafts 222 is extended to the front of the machine where it carries a hand-wheel 228. This single actuating or adjusting means, when turned by the operator, not only moves the cams at the same time but also 10 maintains the carriage-advancing and -retracting inclines 210 and 212 symmetrically disposed with respect to the inactive position of the holder. The accurate presentation and withdrawal of the breast-corners for different sizes of heels is thus 15 insured.

During the time each holder is in a loading and ejecting position, withdrawn from the tool *b* by the cam-surfaces 208 as just described, the table 52 and the prong 38 are lowered to allow the 20 introduction of a heel. This is effected by the cams 42 upon the ends of the sleeves 28 and 40, the latter being rotated continuously by the gearing 170, 172, 176. These cams are of such form, as appears in Fig. 10, that during the loading and 25 unloading periods the sleeve 40 is allowed to descend and with it the spindle 30 and the carrier-sleeve 44, thus separating the table and prong from the pad 80 and leaving a space for the introduction of a heel. The downward movement 30 is under the influence of a helical spring 234 surrounding the spindle 30 and interposed between the upper member of the universal joint 160 and a thrust-bearing 235 abutting against the lower extremity of the sleeve 28. At this 35 time, the operator applies a heel to the table 52 with its breast against the gage 64 and between the arms 66, holding it momentarily. Then, as the holder approaches the point at which the cam-surface 210 allows its carriage to move into the operating position, the contour of the cams 42 causes the sleeves 40 and 44 and the spindle 30 to be forced up against the resistance of the spring 234, so the top-lift strikes the abutment-pad 80. Movement of the table-carrier stops, and the 40 spindle continues to rise to the maximum height produced by the cams 42, compressing the spring 46. The prong 38 is thus forced into the heel-seat-end of the heel, the spring 34 yielding. The 45 heel is now clamped firmly in the holder, with the top-lift at a level determined by the adjustment of the pad 80. The double prong holds it both 50 against transverse displacement upon the table and rotation about a vertical axis. When the holder reaches an unloading position, the cams 42, by their relative rotation, release the table and prong, so the spring 234 lowers them to permit 55 the ejection of the heel.

Were the cams 204 alone depended upon to govern the just-outlined movement of the holder, in absence of an applied heel danger might arise by the contact of the tool with such elements as the rods 82. I guard against this by making the inward travel of each carriage 26 depend upon the presence of a heel in the holder. About the lower portion of each carrier-sleeve 44 is an annular horizontal flange 236 (Fig. 5), presenting at its under side a continuous contact-surface. Guided in the carriage, with its upper end in contact with the flange, is a rod 238 secured at the lower extremity to a hook 240 pivoted at one side of the carriage. A spring 242 urges the hook upwardly, so the engagement of the rod with the flange is maintained. Without a heel in the holder, the carrier-sleeve 44 is elevated by its spring 46, and the correspondingly raised flange

236 permits the rod and hook to assume their uppermost positions. With the carriage 26 at the outer portion of the turret under the control of the cams 204, as it is for the loading of the holder, the hook is at the outer side of a retaining projection 244 fixed to the turret. In this condition the carriage is locked in an inactive position, so the cam-surface 210 will have no effect upon it, and contact of the holder elements with the tool is guarded against. But when the operator inserts a heel in the holder the table 52 and sleeve 44 are thereby lowered, and the flange 236 depresses the rod 238, carrying the hook 240 below its retaining projection. This leaves the cams 204 in full control.

To support the heels and facilitate their application to the holders, an inwardly and upwardly inclined loading platform 250 is provided, the angle approximating that of the heel-seat-ends of the heels in the holders. Its inner edge 20 is curved at *c* on the arc of a circle having its center at the axis of the turret (Fig. 3), lying close to the path of the heel-holders and extending through the loading position. To adjust the platform for different types of heels, it is mounted to tilt upon the frame on trunnions 251 and has a horizontal pin 252 (Figs. 1 and 2) carried at its under side and movable in a slot extending transversely of the upper end of a bar 254 mounted to slide vertically upon the front of the frame. At one edge the bar is formed with rack-teeth 30 engaged by a pinion 256 fast upon a short horizontal shaft 258. The shaft may be turned by a hand-wheel 260 to raise or lower the outer end of the platform. A lever 262 having an eccentric portion bearing upon the bar may be used to clamp said bar in its adjusted position. To enable the operator to conveniently make this adjustment for heels having known characteristics, the platform may have secured to it a vertically extending scale 264 movable along an index-point 266 projecting from the frame. The scale-divisions correspond to the pitches of various heels. Preferably, the scale is made readily removable as by being received in guides at opposite sides of an arcuate holder 268. It may be removed from the holder by a finger-piece 270 at its upper end and replaced by another scale differently graduated to correspond to another group of heel-types.

The platform 250 is shown in Fig. 11 as carrying a gage 265, under the guidance of which the adjustment of the breast-bars 64 of all the heel-holders may be made uniform. There may be applied to the upper face of the platform a readily removable block 267 slotted to receive a shank 269 to which is pivoted the gage 265. The shank is slotted longitudinally and is held adjustably in place upon the block by a set-screw 271. When a change in the heel-form calls for a variation in the gaging means on the heel-holders, the block 267 is positioned on the platform with the gage turned down and located in the correct gaging relation by the screw 271. Then the slide 72 of a holder at the loading position is adjusted to bring the gaging face of its breast-bar into contact with the end of the gage. This having been accomplished, the gage is swung back to its inactive position, clear of the turret, and said turret rotated by the crank 141 to bring the succeeding heel-holder into position and the gaging operation repeated until completed for all the holders. The block and gage are thereupon removed from the platform.

The holder-tables 52 have already been described as being free to tilt on the carriage-sleeves

44 to an extent permitted by their forks 54, to adapt themselves to the inclination of the heels. It is important that while each holder is traveling through the loading position, the outer edge of 5 its table shall be at such a height that the heels will slide upon it from the platform without interference, and that after a heel has been seated upon the table said table shall be so inclined that the tread-surface of the top-lift is substantially 10 parallel to the engaging surface of the pad 80. The arm 56 is therefore so adjusted that the table-edge is normally held by the spring 62 slightly below the adjacent edge of the platform 250, the latter having been properly adjusted for 15 the pitch of the heel being operated upon. Projecting from the under side of the table at its outer edge is an angular finger 272. This, in the loading position of the holder, travels just below a stop or limiting bar 274 (Figs. 3 and 5) 20 lying beneath and transversely of the upper end of the platform and with its inner edge curved to correspond to the path of the finger. The bar has at its extremities upwardly extending arms 276, 276 guided by standards 278 upon the frame 25 to move vertically. Tension-springs 280 joining the bar to the standards draw said bar against the platform. As a consequence of this arrangement, the bar is kept in the same relation to the platform however the latter may be adjusted. 30 The downward and outward projection of the finger 272 is such that as it passes beneath the platform it is always under the bar, and, as the table 52 tilts when the operator slides the heel upon it from the platform, contact of the finger 35 with the bar limits the movement of the table. The angle of the table to the heel-engaging surface of the pad 80 is now substantially that between the heel-seat-end of the heel and its tread-surface, this being one which will correctly present said tread-surface to the pad 80 when the 40 holder closes to clamp the heel. This limiting contact, it will be observed, because of the extension of the bar 274, will be effective during the entire travel of the holder through the loading 45 position.

The finished heels may be discharged, when the holders are opened by the cams 42, in the following manner: Turning about one of the rods 82 of each holder is a compound lever L (Fig. 3) 50 consisting of a main arm 282 upon which is pivoted a contact-arm 284 so arranged that it lies at the inner side of the breast of a heel in the holder, being forced yieldably out by a spring 286 situated between it and the arm 282. This 55 latter arm has an outer cam-edge 288. A torsion-spring 289 surrounding the rod 82 holds the arm 284 away from the heel in the holder and the surface 288 in a position which will cause it to strike a contact-projection 290. This 60 projection is secured by a set-screw 292 in a holder or support 294 for adjustment toward and from the path of the cam-arm 282, while the holder is adjustable upon the frame along the path of the arm by a slot-and-screw connection 296. 65 These adjustments are so made, that just as the cams 42 act to free the heel in a holder the cam-surface 288 contacts with the projection 290, with the result that the arm 284 is swung quickly against the heel. The yield of this arm, because 70 of the spring 286, enables the contact with the heel to be made promptly upon release without danger of injury to the parts. The discharged heel will fall on a chute 298 formed with the loading platform, passing through an opening in 75 said chute into a chute 300 (Fig. 1) secured to

the frame. The discharged heels may be collected in a receptacle 302 removably supported upon a bracket 304 projecting from the frame.

The portions of the operating mechanism B more directly associated with the work are shown in detail in Fig. 8. Through the tubular turret-shaft 22, a tubular shaft 310 extends, carrying near the upper extremity a downwardly recessed plate 312 upon which is secured to rotate with it a cover-plate 314, furnishing a support for the active operating portions of the burnishing tool. Since the peripheries of top-lifts to be operated upon will lie at different angles with respect to the longitudinal axes of diverse types of heels, it is desirable that the operating surface of the tool be angularly adjustable so it may contact accurately with the top-lifts of the heels clamped in the holders. I therefore form the tool sectionally in divided rigid segments 316 arranged in a closely placed series. These segments are pivoted upon a transversely curved circular rib 318 at the periphery of the plate 314, this rib entering a curved slot 320 lying across the under side of each segment. Opening inwardly through each segment from the slot 320 is a radial slot 322 into which extends one of a circular series of upward projections 324 from the plate 314. Upon this mounting the segments 316 may rock and yet be retained against circumferential displacement. Each segment has a peripheral operating surface 326, arranged for contact with the entire width of a top-lift, and an overhanging projection 328 which will extend over the margin of the tread-surface of said top-lift. The contour of the surface 326 longitudinally of the axis of the tool b is constant, corresponding generally to the transverse contour of top-lifts. To hold the segments in place upon the rib 318 with a capacity for angular adjustment, there engages their inner ends inside said rib a circular rib 330 depending from a plate 332 splined to move vertically upon a hub 333 of the plate 314. This hub surrounds a shaft 334 which furnishes a separable continuation of the shaft 310. The rib 330 is forced yieldably against the segments by a spring 336, which is about the hub 333 and abuts at its upper extremity against a collar 338 threaded upon said hub. Change in the vertical position of the collar varies the force exerted by the spring upon the segments to raise their outer portions. This movement is resisted and governed by the contact with the segments outside the rib 318 of an annular rib 340 upon the outside of a ring 342 surrounding the plate 332 and having its hub 344 splined to the hub 333. The tendency of the spring 336, acting through the segments, is to force the ring up, but this is resisted by contact of the hub 344 with a hand-wheel 346 threaded upon the upper extremity of the hub 333. Consequently, rotation of this hand-wheel will either cause the operating surfaces of all the segments to be simultaneously lowered or will permit the spring 336 to raise them. In this way the angle of all the surfaces 326 will be altered to the same extent, while the practical continuity of the burnishing periphery of the tool remains unaltered. A hand-nut 350, threaded upon the upper extremity of the shaft 334, holds the tool-assembly against displacement. 60 65 70 75

To impart to the segment-surfaces 326 the proper burnishing temperature, there may be situated in the recess of the plate 312 a circular electrical heating unit 352. Two conductors 354, supplying current to this unit, pass through the shaft 310 and are brought out below the sur- 75

rounding shaft 22 to two collector-rings 358 (Fig. 7). Contacting with these rings are brushes 358 carried by a casing 360. The current-delivering device, consisting of the rings, casing 5 and brushes, is so mounted that it may move vertically as a unit with the shaft 310. The brushes are joined by conductors in a flexible cable 362 to a junction-box 364 (Fig. 1).

The burnishing tool should be capable of adjustment vertically for action upon the top-lifts of heels of different heights. The shaft 310 has fixed to it two collars 370, 370, lying upon opposite sides of a supporting yoke 372 (Fig. 2) between the arms of which the casing 360 is mounted. Opposite extremities of the yoke are guided for vertical movement by rods 374, 374 secured in the frame. Between these rods the yoke has a vertical threaded opening to receive a screw 376 rotatable in the frame. The screw is shown as 20 turned through bevel-gearing 378, a horizontal shaft 380 and a hand-wheel 382 upon said shaft at the front of the frame. Rotation of the hand-wheel turns the screw 376 in one direction or the other, correspondingly raising or lowering the yoke, and thus altering the vertical position of the burnishing tool. In connection with this adjustment of the tool, the heel-clamping pads 80 will first be adjusted to the desired uniform height by their hand-wheels 92. To facilitate 30 this, there may be used as a gage a bar 384 (Fig. 1) arranged to be turned from an inactive to an active position about a standard 386, rising from the frame at one side of the turret and carrying a collar 387 upon which the bar rests. The collar 35 may be secured at different heights by a set-screw 388. The pads 80 having been positioned under the guidance of this gage, when it is swung into proximity to the path of the holders, the tool may be correspondingly adjusted by turning 40 its hand-wheel 382. Below the yoke 372 the shaft 310 passes through a bearing 390 in the frame (Fig. 7), and beneath this bearing power is applied to the shaft to rotate it, and the tool b, continuously during the operation of the machine. This is directly effected by spiral gearing 45 392 joining it to the driving shaft 100. The arrow in Fig. 3 shows the resulting direction of rotation of the tool. It is the same as that of the turret 24 and opposite to the rotation of the heel-holding platforms 52. The shaft 310 is splined to move vertically through its gear during the adjustment resulting from the movement 50 of the yoke 372.

To outline the operation of the machine, and 55 assuming that the type or size of heel the top-lifts of which are to be burnished is changed, the operator disconnects the driving shaft 100 from the turret 24 by depressing the treadle 152, this joining said turret to the shaft 140. By the 60 crank 141 each of the heel-clamping holders 52, 80 may be brought into the loading position opposite the platform 250, and by the gaging members 265 and 384 the heel-locating means of the clamping table 52 and the pressure-abutments 80 are respectively adjusted to place the heel clamped in the holder in correct relation 65 to receive the action of the tool b. Said tool is also adjusted vertically by the hand-wheel 382 to correspond to the tread-abutments, and the 70 angle of the burnishing periphery of its sections 316 caused to agree with the edge of the heel-lift through rotation of the hand-wheel 346. By the hand-wheel 260, the angle of the loading platform is caused to correspond to that of the heel-seat-end of the heel in the holder when its

tread-surface is resting against the abutment 80. Through adjustment of the arm 58, each table 52 is brought to a position in which its finger 272 will pass somewhat below the platform-controlled bar 274. The treadle 152 may now be released from its latch 154 and the belt-shifter 104 actuated to apply power to the driving shaft 100. This produces continuous rotation of the turret, revolving the heel-holders and at the same time rotating them about their respective vertical axes upon their carriages 26 movable radially of the turret by the springs 192 and 196. As each holder passes the loading position opposite the platform 250 and the unloading position immediately preceding this and opposite the chute 15 298, contact of the roll 206 of its carriage with cams 204 moves said holder outwardly away from the tool. Upon this movement, holder-cams 42 separate the clamping members 52 and 80 for the discharge and reception of the heels. With 20 a holder thus traveling open along the platform, the operator takes a heel H from a tray 400 (Fig. 1), supported at one side of the machine by a bracket 402, and places it heel-seat-end down upon the platform 250. He then slides the 25 heel inwardly and in the direction of advance of the holder until it rests upon the passing table 52 with its breast against the bar 72 and its sides held by the gages 66. By the uniform rotation of the holder once during each revolution by the 30 turret, the breast-bar 64 is held always parallel to the front of the machine, so the introduction to and positioning of heels in the holder is facilitated. At this time the cams 42 release the table, the spring 234 carrying the tread-surface of the 35 top-lift T against the abutment 80. The double prong 38 is forced into the heel to make its retention certain.

It may be found that the operator is not sufficiently deft to render certain the application of 40 the heels to the traveling holders. In that case, there may be added a loading device which operates, in part, under the power of the machine. As shown in Figs. 3 and 11, there is formed in the platform 250 and extending into the chute 45 298, a transverse slot 404, the direction of extension of which is also inwardly, approximating that in which the operator would advance the heel in purely manual loading. In the slot a slide 406 is mounted to move. Secured to the 50 slide above the platform is a transverse bar 408, to the outer extremity of which is pivoted a heel-positioning contact member 410. This member may be fixed at different angles across the slide by a set-screw 411 threaded through the bar 408 and bearing upon a projection 412 from the member. A block 414 depends from the slide through the slot (Fig. 12) and has adjustably secured to it by a set-screw 416 a finger 418, for projection to different extents toward the 55 turret. From the carrier-sleeve 44 of each holder is a projection 420, the path of which in the rotation of the turret and of the holder brings it into contact with the slide-finger. Consequently, the passage of each holder past the loading platform causes the slide to move in registration with it transversely of its path of advance, and then, as the holder-projection slips past the end of the finger, to release said slide. This is shown as returned to a normal position by a 60 spring 422, with the bar 408 resting against a wall 424 dividing the loading platform from the discharge chute. The spring may be of the helical type, joined at its ends to the under side of the 65 chute and to the finger 418. A pad 426 of some 70 75

yieldable material such as leather may be interposed as a bumper between the bar and the wall. This pad may be extended to the opposite side of the wall at 427 to serve as a cushion or stop for heels ejected violently from the holders, as may sometimes occur. It will be seen that during the travel of each heel-holder past the loading platform, the engagement of the holder- and slide-projections will cause the slide and its member 410 to move with it. By adjustment of the projection or finger 418, the release of the slide may be caused to occur just after the heel is clamped in the holder. Therefore, with the member 410 adjusted as to angle to best present a heel to the holder, the operator needs only to slide the heel in under its guidance until said heel is seated upon the table 52, the travel of the member 410 maintaining the heel in proper loading alignment with the table during the travel of the latter along the platform. To do this, no particular skill is necessary.

The heel having been clamped, the holder is released by the cams 204 and carried into burnishing engagement with the tool *b*. The springs which effect this movement are, however, only permitted to act if the holder has received its heel. In the loading and unloading positions of the holders, each is locked out against the force of the springs by its hook 240, which is released only as the application of a heel to the holder depresses the sleeve 44 and the rod 238. Passing from the loading to the operating position, the cam-incline 210 allows contact of the clamped heel with the surface 326 of the tool just as the rotation of the holder brings one breast-corner opposite said surface. Rotation of the tool and rotation of the holder causes the curved periphery of the heel to receive the burnishing action until the opposite cam-incline 212 removes the holder from active co-operation with the tool at the opposite breast-corner. The unloading position has then been reached; the cams 42 unclamp the heel; and contact of the lever *L* of the holder with the stationary projection 290 ejects the heel into the chute 298, to be conducted over the chute 300 to the receptacle 302. The holder now arrives at the loading position, having been both revolved and rotated through 360°, and is ready for the reception of another heel. While the action of the tool has been described in connection with a single heel only, inspection of Fig. 3 of the drawings will make it clear that the burnishing of the heels in three holders is taking place simultaneously, while the fourth holder is discharging its heel and being again supplied.

Some shoe manufacturers prefer to use an oscillatory rather than a rotary burnishing tool. To meet this requirement, I have provided means for the ready conversion of the movement of the tool *b* from one type to the other. Fig. 13 illustrates connections for producing oscillation of the tool. Here the spiral gearing 392 has been removed and an arm 432 secured to the tool-shaft 310. Fixed in vertical bores in the frame are spindles 434, 434 spaced from one another and having turning upon them a yoke 436. In this yoke a horizontal shaft 438 is rotatable. One extremity of this shaft is joined by a link 440 to the arm 432. Clamped upon the shaft between the arms of the yoke is a head 442 having a cylindrical extension 444 entering an inclined bore in an enlargement 445 at the inner end of the shaft 100. As this shaft 100 rotates, the revolution of the inclined member 444 will oscillate the head 442 both vertically and horizontally and will com-

municate the latter motion to the yoke 436. This is transmitted through the link 440 to the arm 432 on the tool-shaft 310. The tool is thus caused to move back and forth in relatively short strokes across the work, which may be presented to it in precisely the manner already described in connection with the rotation of the tool. The arrangement for either form of actuation requires no alteration of the structure of the machine but merely the interchange of a few simple and readily accessible elements.

Having described the invention, what is claimed as new and desired to be secured by Letters Patent of the United States is:

1. In a machine for operating upon shoe-heels, a plurality of traveling heel-holders, and a movable tool for operating simultaneously upon the heels in plural holders. 15
2. In a machine for operating upon shoe-heels, a movable tool, a heel-holder traveling about the tool, and means for rotating the heel-holder during its travel. 20
3. In a machine for operating upon shoe-heels, a movable tool, and a heel-holder traveling about the tool and mounted for bodily movement with respect to the tool. 25
4. In a machine for operating upon shoe-heels, a movable tool, a plurality of heel-holders traveling about the tool, and means for rotating each holder during its travel. 30
5. In a machine for operating upon shoe-heels, a movable tool, a plurality of heel-holders traveling about the tool, and means for rotating each holder during its travel, each holder being bodily movable toward and from the tool independently of the associated holders. 35
6. In a machine for operating upon shoe-heels, a rotatable tool, a plurality of heel-holders revoluble about the tool, and means acting during such revolution for rotating each holder about an axis extending longitudinally of the contained heel. 40
7. In a machine for operating upon shoe-heels, a movable tool, a plurality of heel-holders revoluble about the tool, and means acting during such revolution for rotating each holder in a direction opposite to its revolution about an axis extending longitudinally of the contained heel. 45
8. In a machine for operating upon shoe-heels, an oscillatory tool, a plurality of heel-holders revoluble about the tool, and means acting during such revolution for rotating each holder about an axis extending longitudinally of the contained heel. 50
9. In a machine for operating upon shoe-heels, a movable tool, a plurality of heel-holders revoluble about the tool, and means for rotating each holder about an axis extending longitudinally of the contained heel, such rotation occurring once during each revolution of the holder. 55
10. In a machine for operating upon shoe-heels, a movable tool, a plurality of heel-holders revoluble about the tool, and means for rotating each holder about an axis extending longitudinally of the contained heel, such rotation occurring once during each revolution of the holder and at a uniform speed. 60
11. In a machine for operating upon shoe-heels, a series of heel-holders, means for moving the holders in a closed path continuously during the operation of the machine, means for continuously rotating each holder during its travel, and a movable tool for operating upon the traveling heels. 65
12. In a machine for operating upon shoe-heels, a plurality of heel-holders, means for moving the holders in a closed path continuously during the operation of the machine, means for continuously rotating each holder during its travel, and a movable tool for operating upon the traveling heels. 70
13. In a machine for operating upon shoe-heels, a plurality of heel-holders, means for moving the holders in a closed path continuously during the operation of the machine, means for continuously rotating each holder during its travel, and a movable tool for operating upon the traveling heels. 75

12. In a machine for operating upon shoe-heels, a series of heel-holders, means for moving the holders in a closed path continuously during the operation of the machine, means for continuously rotating each holder during its travel, a movable tool, and means for moving the tool in simultaneous engagement with the series of travelling heels.
13. In a machine for operating upon shoe-heels, a movable tool, a heel-holder revoluble about the tool, and means for maintaining the holder in a constant angular relation about its axis with respect to a relatively fixed line past which said holder revolves altering its distance therefrom in such travel.
14. In a machine for operating upon shoe-heels, a movable tool, a heel-holder revoluble about the tool, and means for maintaining the holder in a constant angular relation about its axis with respect to the front of the machine.
15. In a machine for operating upon shoe-heels, a movable tool, a heel-holder revoluble about the tool, and means for maintaining the holder in a constant angular relation about its axis with respect to the line along which heels are introduced into said holder.
16. In a machine for operating upon shoe-heels, a movable tool, a plurality of heel-holders revoluble about the tool, and means for maintaining all the holders during their revolution in a constant angular relation about axes extending longitudinally of the contained heels.
17. In a machine for operating upon shoe-heels, a movable tool, a plurality of heel-holders revoluble about the tool and each having a breast-gage, and means for maintaining all the holders with their breast-gages substantially parallel to the front of the machine.
18. In a machine for operating upon shoe-heels, a movable tool, a plurality of heel-holders revoluble about the tool, means for facilitating the loading of the heels into the holders, and means for maintaining all the holders during their revolution in a constant angular relation to the loading means about axes extending longitudinally of the contained heels.
19. In a machine for burnishing the top-lifts of shoe-heels, a rotatable turret, a generally circular tool movable at the axis of the turret, and plural heel-holders carried by the turret and all co-operating with the tool.
20. In a machine for burnishing the top-lifts of shoe-heels, a rotatable turret, a generally circular tool movable at the axis of the turret, plural heel-holders carried by the turret and all co-operating with the tool, and means for rotating each holder upon the turret.
21. In a machine for burnishing the top-lifts of shoe-heels, a rotatable turret, a burnishing tool rotatable about the axis of the turret, and plural heel-holders carried by the turret and all co-operating with the tool.
22. In a machine for burnishing the top-lifts of shoe-heels, a rotatable turret, a tool movable in opposite directions, and plural heel-holders carried by the turret in simultaneous co-operation with the tool.
23. In a machine for burnishing the top-lifts of shoe-heels, a rotatable turret, a generally circular tool movable at the axis of the turret, heel-holders rotatable upon the turret, a gear fixed relatively to said turret, and gearing rotatable upon the turret and joining the fixed gear to the holders.
24. In a machine for burnishing the top-lifts of shoe-heels, a rotatable turret, a generally circular tool movable at the axis of the turret, heel-holders rotatable upon the turret, and gearing for rotating each heel-holder once during each rotation of the turret.
25. In a machine for operating upon shoe-heels, a movable tool, a carriage traveling about and movable toward and from the tool, a heel-holder rotatable upon the carriage, and means for rotating the holder during the travel of the carriage.
26. In a machine for operating upon shoe-heels, a movable tool, a plurality of carriages traveling about and movable toward and from the tool, a heel-holder rotatable upon each carriage, and means for rotating the holders during the travel of the carriages.
27. In a machine for operating upon shoe-heels, a plurality of traveling heel-holders, a movable tool for operating simultaneously upon the heels in plural holders, and means for moving all the carriages toward the tool.
28. In a machine for operating upon shoe-heels, a rotatable tool, a plurality of heel-holders revoluble about the tool, a carriage for each holder movable radially with respect to the axis of revolution, and means acting during the revolution for rotating each holder upon the carriage about an axis extending longitudinally of the contained heel.
29. In a machine for operating upon shoe-heels, a series of heel-holders, means for moving the holders in a closed path continuously during the operation of the machine, means for moving each holder laterally of the path, means for continuously rotating each holder during its travel, and a movable tool for operating upon the travelling heels.
30. In a machine for operating upon shoe-heels, a movable tool, a plurality of carriages revoluble about the tool, a heel-holder rotatable upon each carriage, means governed by the contour of a heel in each holder for moving the carriage and heel toward the tool, and means for rotating each holder upon the carriage.
31. In a machine for operating upon shoe-heels, a movable tool, a plurality of carriages revoluble about the tool, a heel-holder rotatable upon each carriage, means governed by the contour of a heel in each holder for moving the carriage and heel toward the tool, and means for maintaining all the holders during their revolution in a constant angular relation about axes extending longitudinally of the heels.
32. In a machine for burnishing the top-lifts of heels, a rotatable turret, a tool movable at the axis of the turret, a plurality of carriages movable upon the turret, and a heel-holder rotatable upon each carriage and co-operating with the tool.
33. In a machine for burnishing the top-lifts of heels, a rotatable turret, a burnishing tool rotatable about the axis of the turret, a plurality of carriages movable upon the turret radially with respect to the tool, and a heel-holder rotatable upon each carriage and co-operating with the tool.
34. In a machine for operating upon shoe-heels, a tread-abutment, a carrier movable toward and from the abutment, a table pivoted upon the carrier opposite the abutment and arranged for contact with the heel-seat-end of a heel, a breast-gage secured to the table, and side-gages yieldable at opposite sides of the table.

35. In a machine for operating upon shoe-heels, a tread-abutment, a carrier movable toward and from the abutment, a table pivoted upon the carrier opposite the abutment and arranged for contact with the heel-seat-end of a heel, a slide movable upon the table, and a breast-gage and side-gages carried by the slide and being adjustable together with reference to the tread-abutment as the pitch of the heels being operated upon changes.
36. In a machine for operating upon shoe-heels, a tread-abutment, a carrier movable toward and from the abutment, a table pivoted upon the carrier opposite the abutment and arranged for contact with the heel-seat-end of a heel, a slide movable upon the table, heel-gaging means carried by the slide, and means for clamping the slide in different positions upon the table.
37. In a machine for operating upon shoe-heels, a tread-abutment, a carrier movable toward and from the abutment, a table pivoted upon the carrier opposite the abutment and arranged for contact with the heel-seat-end of a heel, gaging means secured to the table for engagement with the heel, means adjustably limiting the pivotal movement of the table, and means for normally holding the table at one of its extremes of movement.
38. In a machine for operating upon shoe-heels, a tread-abutment, a carrier movable toward and from the abutment, a table pivoted upon the carrier opposite the abutment and arranged for contact with the heel-seat-end of a heel, a fork extending from the table, and a stop variable in position upon the carrier between the branches of the fork.
39. In a machine for operating upon shoe-heels, a tread-abutment, a carrier movable toward and from the abutment, a table pivoted upon the carrier opposite the abutment and arranged for contact with the heel-seat-end of a heel, a fork extending from the table, an arm turning upon the pivot of the table and extending between the branches of the fork, and a detent movable upon the arm and engaging the carrier.
40. In a machine for operating upon shoe-heels, a rotatable turret, carriages movable radially of the turret, uprights rising from the opposite sides of each carriage, a table pivoted upon the carriage, and an abutment mounted upon the uprights opposite the table.
41. In a machine for operating upon shoe-heels, a rotatable turret, carriages movable radially of the turret, uprights rising from the opposite sides of each carriage, a table pivoted upon the carriage, a yoke connecting the uprights, and an abutment rotatable upon the yoke opposite the table.
42. In a machine for operating upon shoe-heels, a rotatable turret, carriages movable radially of the turret, uprights rising from the opposite sides of each carriage, a table pivoted upon the carriage, a yoke connecting the uprights, a screw threaded through the yoke, a slide movable upon the uprights by the screw, and an abutment mounted upon the slide opposite the table.
43. In a machine for operating upon shoe-heels, a movable tool, a rotatable turret, heel-holders rotatable upon the turret and co-operating with the tool, a main driving shaft, a shaft arranged to be rotated manually, and means arranged to connect selectively either shaft to the turret to effect its rotation.
44. In a machine for operating upon shoe-heels, a movable tool, a rotatable turret, heel-holders rotatable upon the turret and co-operating with the tool, a main driving shaft, a shaft upon which the turret is supported, a shaft arranged to be rotated manually, two intermediate shafts, gearing connecting one intermediate shaft to the turret-shaft, gearing connecting the other intermediate shaft to the manually rotatable shaft, and means for selectively connecting the first intermediate shaft to either the driving shaft or the second intermediate shaft.
45. In a machine for operating upon shoe-heels, a movable tool, a rotatable turret, heel-holders rotatable upon the turret and co-operating with the tool, a main driving shaft, a shaft upon which the turret is supported, a shaft arranged to be rotated manually, an intermediate shaft, a tubular shaft surrounding said intermediate shaft, gearing connecting the intermediate shaft to the turret-shaft, gearing connecting the tubular shaft to the manually rotatable shaft, and a clutch arranged to connect the intermediate shaft to either the driving shaft or the tubular shaft.
46. In a machine for operating upon shoe-heels, a movable tool, a carriage revoluble about and movable toward and from the tool, a heel-holder rotatable upon the carriage, means for rotating the holder during the travel of the carriage and a spring exerting a constant force to move the carriage toward the tool.
47. In a machine for operating upon shoe-heels, a movable tool, a carriage revoluble about and movable toward and from the tool, a heel-holder rotatable upon the carriage, means for rotating the holder during the travel of the carriage, a spring exerting a constant force to move the carriage toward the tool, and means arranged to vary the force of the spring.
48. In a machine for operating upon shoe-heels, a movable tool, a turret rotatable about an axis at the tool, work-carriages movable upon the turret, a spring mounted upon each carriage, and gearing connecting the spring and turret.
49. In a machine for operating upon shoe-heels, a movable tool, a turret rotatable about an axis at the tool, work-carriages movable upon the turret, a spring mounted upon each carriage, gearing connecting the spring and turret, and means arranged to vary the connection of each spring to its carriage.
50. In a machine for operating upon shoe-heels, a movable tool, a turret rotatable about an axis at the tool, work-carriages movable upon the turret, a spindle rotatable upon each carriage, a spring connecting the spindle and carriage, means for retaining each spindle in different angular positions about its axis, and gearing connecting said spindle to the turret.
51. In a machine for operating upon shoe-heels, a movable tool, a carriage revoluble about and movable toward and from the tool, a heel-holder rotatable upon the carriage, means for rotating the holder during the travel of the carriage, and a tension-spring joining each side of the carriage to the turret.
52. In a machine for operating upon shoe-heels, a movable tool, a carriage revoluble about and movable toward and from the tool, a heel-holder rotatable upon the carriage, means for rotating the holder during the travel of the carriage, a tension-spring joining each side of the carriage to the turret, and means arranged to vary the point of attachment of one extremity of each spring.
53. In a machine for operating upon shoe-heels,

- 5 a movable tool, a rotatable turret, a plurality of heel-holders revolved by the turret about the tool, said heel-holders being rotatable upon the turret and movable on said turret toward and from the 5 tool, and means for controlling the movement of the holders with respect to the tool.
54. In a machine for operating upon shoe-heels, a movable tool, a rotatable turret, a plurality of heel-holders rotatable upon the turret and movable on said turret toward and from the 10 tool, and means fixed relatively to the turret and acting upon one only of the heel-holders at a time to remove it from the tool, the other holders being left free to present heels to said tool.
- 15 55. In a machine for operating upon shoe-heels, a movable tool, a rotatable turret, a plurality of heel-holders rotatable upon the turret and movable on said turret toward and from the 15 tool, means for controlling the movement of the holders with respect to the tool, and means arranged to cause the controlling means to act through different lengths of time in the rotation of the turret.
- 20 56. In a machine for operating upon shoe-heels, a movable tool, a rotatable turret, carriages movable upon the turret, heel-holders rotatable upon the carriages in co-operation with the tool, a cam normally fixed against movement and acting to move the carriages, and 25 means arranged to vary the position of the cam circumferentially of the turret to control the initiation and termination of the operation upon each heel.
- 30 57. In a machine for operating upon shoe-heels, a movable tool, a rotatable turret, carriages movable upon the turret, heel-holders rotatable upon the carriages in co-operation with the tool, a cam comprising a plurality of sections 35 acting upon the carriages, and means for simultaneously adjusting the cam-sections to different positions.
- 40 58. In a machine for operating upon shoe-heels, a movable tool, a rotatable turret, carriages movable upon the turret, heel-holders rotatable upon the carriages in co-operation with the tool, a cam comprising a plurality of sections acting upon the carriages, and an actuating member common to the sections and by which 45 they may be moved simultaneously in opposite directions.
- 50 59. In a machine for operating upon shoe-heels, a movable tool, a rotatable turret, a plurality of heel-holders movable by the turret in co-operation with the tool through a loading 55 and unloading position and an operating position, means for normally moving the holders toward the tool, and means for withdrawing said holders from the tool at the loading and unloading position.
- 60 60. In a machine for operating upon shoe-heels, a movable tool, a rotatable turret, a plurality of heel-holders movable by the turret in co-operation with the tool through a loading and unloading position and an operating position, 65 means for normally moving the holders toward the tool, means for withdrawing said holders from the tool at the loading and unloading position, and means for causing the action of the withdrawing means at different points in the rotation of the turret.
- 70 61. In a machine for burnishing the top-lifts of heels, a movable burnishing tool, a turret rotatable about an axis at the tool, a plurality of carriages movable radially of the turret, a heel-holder rotatable upon each carriage, means for 75 normally moving the carriages to bring the holders into co-operation with the tool, and means acting upon the carriages to withdraw the holders from the tool during the presentation thereto of the breast-portion of the top-lift. 5
62. In a machine for burnishing the top-lifts of heels, a movable burnishing tool, a turret rotatable about an axis at the tool, a plurality of carriages movable radially of the turret, a heel-holder rotatable upon each carriage, means for 10 normally moving the carriages to bring the holders into co-operation with the tool, means acting upon the carriages to withdraw the holders from the tool during the presentation thereto of the breast-portion of the top-lift, and means arranged to vary the extent of top-lift-periphery upon which the tool acts. 15
63. In a machine for burnishing the top-lifts of heels, a movable burnishing tool, a turret rotatable about an axis at the tool, a plurality of 20 carriages movable radially of the turret, a heel-holder rotatable upon each carriage, a spring acting upon each carriage to urge it towards the tool, and a normally fixed cam into engagement with which the carriages are moved by the 25 turret. 25
64. In a machine for burnishing the top-lifts of heels, a movable burnishing tool, a turret rotatable about an axis at the tool, a plurality of carriages movable radially of the turret, a heel-holder rotatable upon each carriage, a spring acting upon each carriage to urge it towards the tool, and a normally fixed cam into engagement with which the carriages are moved by the 30 turret, said cam having a portion concentric 35 with the axis of the turret and terminal portions inclined inwardly therefrom. 35
65. In a machine for burnishing the top-lifts of heels, a movable burnishing tool, a turret rotatable about an axis at the tool, a plurality of 40 carriages movable radially of the turret, a heel-holder rotatable upon each carriage, a spring acting upon each carriage to urge it towards the tool, a normally fixed cam into engagement with which the carriages are moved by the 45 turret, said cam having overlapping movable sections, gearing connecting the sections, and means arranged for manual actuation and connecting the gearing of the sections. 45
66. In a machine for operating upon shoe-heels, a heel-holder having opposed heel-clamping members and being rotatable about an axis passing through it and through a clamped heel, means whereby the rotation of the holder produces a force urging one of the members toward the other, and means made effective by the rotation of the holder for separating the members. 50 55
67. In a machine for operating upon shoe-heels, a support provided with a cam, and a heel-clamping member rotatable upon the support in one direction only and having a cam movable in contact with the support-cam, both of said cams surrounding the axis of rotation of the member and acting as said member turns to both clamp and release a heel. 60 65
68. In a machine for operating upon shoe-heels, a support provided with a cam, a heel-clamping member rotatable upon the support and having a cam movable in contact with the cam of the support, and a spring interposed between the member and the support and holding the cams in engagement. 70
69. In a machine for operating upon shoe-heels, a support provided with a cam, a spindle rotatable upon the support and having a cam 75

contacting with the support-cam, and a heel-clamping member pivotally mounted upon the spindle.

70. In a machine for operating upon shoe-
5 heels, a support provided with a cam, a spindle
rotatable upon the support and having a cam con-
tacting with the support-cam, a heel-engaging
table pivotally mounted upon the spindle, and a
yieldable prong projecting through the table

10 71. In a machine for operating upon shoe-heels, a support provided with a cam, a spindle rotatable upon the support and having a cam contacting with the support-cam, a sleeve yieldable upon the spindle, and a heel-clamping member pivoted upon the sleeve.

15 ber pivoted upon the sleeve.

72. In a machine for operating upon shoe-heels, a support provided with a cam, a spindle rotatable upon the support and having a cam contacting with the support-cam, a sleeve yieldable upon the spindle, a heel-engaging table pivoted upon the sleeve, and a plunger yieldable in the spindle and having a prong projecting through the table.

73. In a machine for operating upon shoe-
heels, a traveling heel-holder having opposite
25 heel-clamping members, opposite relatively mov-
able members traveling with the holder and hav-
ing their relative movement only in portions of
such travel for separating the clamping members
30 and means traveling with the holder and being
movable independently of such travel for con-
trolling the clamping members.

35 74. In a machine for operating upon shoe-heels, a traveling heel-holder having opposite heel-clamping members, means for rotating the holder during its travel, and means made effective by the rotation of the holder for controlling the clamping members.

40 75. In a machine for operating upon shoe-heels, a traveling heel-holder having opposite heel-clamping members, and a plurality of cams traveling with and individual to the holder and movable relatively to each other under the power of the machine to change the clamping action of the members.

45 76. In a machine for operating upon shoe-
heels, a traveling heel-holder having opposite
heel-clamping members, a plurality of cams
traveling with and individual to the holder and
movable upon said holder relatively to each
50 other, and means for continuously producing such
compound movement with and upon the holder.

77. In a machine for operating upon shoe-heels, a traveling heel-holder having opposite heel-clamping members, means for rotating the holder during its travel, a non-rotatable cam traveling with the holder, and a cam rotatable with the holder and contacting with the non-rotatable cam.

60 78. In a heel-burnishing machine, a rotatable turret, a series of heel-holders movable by the turret through a loading position and an operating position, and means movable continuously upon and relatively to the turret during its advance by the rotation of said turret for supplying forces for clamping in the holders in the operating position heels received at the loading position.

79. In a heel-burnishing machine, a rotatable turret, a series of holders having opposite heel-clamping members movable by the turret through a loading position and an operating position, and a pair of cam members carried by the turret and movable relatively to each other under the power of the machine to clamp in the holders at the

operating position heels received at the loading position.

80. In a heel-burnishing machine, a rotatable turret, a series of holders having opposite heel-clamping members rotatable upon the turret through a loading position and an operating position, a cam associated with each holder and fixed against rotation upon the turret, and a cam rotatable with each holder and contacting with the fixed cam.

81. In a machine for operating upon shoe-heels, a tool, heel-holders movable into co-operation with the tool, means for preventing such movement, and means dependent upon the application of a heel to the holder for releasing the movement-preventing means. 15

82. In a machine for operating upon shoe-heels, a traveling heel-holder movable laterally of the path of advance, means for imparting the lateral movement to the holder, means for normally preventing such movement, and means controlled by the application of a heel to the holder for releasing the movement-preventing means. 20

83. In a machine for operating upon shoe-heels, a tool, rotatable heel-holders movable in co-operation with the tool, means for preventing such movement, and a member rotatable with the holder and movable into engagement with the movement-preventing means to effect its release. 30

84. In a machine for operating upon shoe-heels, a tool, a carriage movable toward and from the tool, a heel-holder rotatable upon the carriage, a spring urging the carriage toward the tool, a lock joining the carriage to the turret to maintain the holder against the force of the spring, and means acted upon by the holder for releasing the carriage.

85. In a machine for operating upon shoe-heels, a tool, a rotatable turret, a series of heel-holders each movable upon the turret toward and from the tool, and means controllable by the application of a heel to each holder for permitting such movement of said holder.

86. In a machine for operating upon shoe-
heels, a tool, a rotatable turret, a series of car-
riages movable upon the turret toward and from
the tool, a holder mounted upon each carriage
and having relatively movable heel-clamping
members, and means for locking each carriage
upon the turret at a point removed from the
tool, a clamping member of each holder having a
portion contacting with the locking means to
release the carriage. 45 50

87. In a machine for operating upon shoe-
heels, a tool, a rotatable turret, a series of car-
riages movable upon the turret toward and from
the tool, a holder mounted upon each carriage
and having relatively movable heel-clamping
members, a locking member movable upon each
carriage, and a retaining member fixed to the
turret for engagement by the locking member, the
locking member being movable by one of the
clamping members to release it from the retain-
ing member. 60

88. In a machine for operating upon shoe-heels, a tool, a rotatable turret, a series of carriages movable upon the turret toward and from the tool, a holder mounted upon each carriage and having relatively movable heel-clamping members, means for locking each carriage upon the turret upon a point removed from the tool, a rotatable holder mounted upon each carriage and having a movable heel-clamping member and a relatively fixed heel-clamping member, a 70

- locking member movable upon each carriage, and a retaining member fixed to the turret for engagement by the locking member, the movable clamping member having a portion acting during its rotation upon the locking member.
89. In a machine for operating upon shoe-heels, a tool, a rotatable turret, a series of carriages movable upon the turret toward and from the tool, heel-holders rotatable upon each carriage, each holder having an annular flange, a hook pivoted upon each carriage for retaining engagement with the turret, and a rod rising from the hook and receiving contact of the holder-flange.
90. In a machine for operating upon shoe-heels, a movable tool, a rotatable turret, a plurality of heel-holders movable upon said turret toward and from the tool, means for controlling the movement of the holders with respect to the tool, and means for temporarily locking the holders out of co-operation with the tool.
91. In a machine for operating upon shoe-heels, a movable tool, a rotatable turret, a plurality of holders rotatable upon the turret and movable on said turret toward and from the tool, means fixed relatively to the turret for controlling the movement of the holders with respect to the tool, and means carried by the turret for temporarily locking the holders out of co-operation with the tool.
92. In a machine for operating upon shoe-heels, a movable tool, a rotatable turret, a plurality of holders rotatable upon the turret and movable on said turret toward and from the tool, the holders being carried by the turret through loading and operating positions, means for removing the holders from co-operation with the tool in the loading position and permitting such co-operation in the operating position, and means for locking the holders out of co-operation with the tool in the operating position.
93. In a machine for operating upon shoe-heels, a movable tool, a rotatable turret, a plurality of holders rotatable upon the turret and movable on said turret toward and from the tool, the holders being carried by the turret through loading and operating positions, means made effective in the rotation of the turret for removing the holders from co-operation with the tool in the loading position and permitting such co-operation in the operating position, and means dependent upon the absence of a heel in position on a holder for locking such holder out of co-operation with the tool in the operating position.
94. In a machine for operating upon shoe-heels, a tool, a holder traveling continuously in the operation of the machine to present a contained heel to the tool, and a heel-support extending along the path of the holder, said support being arranged to direct into the holder a heel moved over it by the operator, the support being inclined to generally correspond to the inclination of the heel-seat-end of the heel in the holder.
95. In a machine for operating upon shoe-heels, a tool, a holder traveling continuously in the operation of the machine to present a contained heel to the tool, a heel-support extending along the path of the holder, said support being arranged to direct into the holder a heel moved over it by the operator, the support being inclined to generally correspond to the inclination of the heel-seat-end of the heel in the holder, and means arranged to adjust the angle of support to adapt it for use with different types of heels.
96. In a machine for operating upon shoe-heels, a tool, a holder traveling continuously in the operation of the machine to present a contained heel to the tool, a heel-support extending along the path of the holder, said support being arranged to direct a heel moved over it by the operator into the holder, the support being inclined to generally correspond to the inclination of the heel-seat-end of the heel in the holder, means arranged to adjust the angle of support to adapt it for use with different heels, and an index-point and scale-holder movable relatively to each other upon variation of the angle of the support, the scale-holder being arranged to receive scales graduated to correspond to groups of heels having different pitches.
97. In a machine for burnishing the top-lifts of heels, a movable burnishing tool, a rotatable turret co-operating with the tool, a series of heel-holders carried by the turret and having inclined tables, and a platform past the inner edge of which the tables are successively advanced, said platform being inclined to generally correspond to the inclination of the heel-seat-ends of heels in the holders.
98. In a machine for burnishing the top-lifts of heels, a movable burnishing tool, a rotatable turret co-operating with the tool, a series of heel-holders carried by the turret and having inclined tables, a platform past the inner edge of which the tables are successively advanced, said platform being inclined to generally correspond to the inclination of the heel-seat-ends of heels in the holders, a pivotal mounting for the platform, and means arranged to hold the platform at different angles upon its mounting.
99. In a machine for operating upon shoe-heels, a tool, a holder traveling to present a heel to the tool, said holder having a heel-clamping member variable in its angular position, and means past which the holder travels for limiting the angular movement of the clamping member.
100. In a machine for operating upon shoe-heels, a tool, a holder traveling to present a heel to the tool, said holder having a heel-clamping member variable in its angular position, means traveling with the holder for maintaining the clamping member at a predetermined limit in one direction, and means past which the holder travels for limiting the angular movement of the clamping member to a predetermined extent in the opposite direction.
101. In a machine for operating upon shoe-heels, a tool, a holder traveling to present a heel to the tool, said holder having a tread-abutment and an opposite heel-seat-end-engaging table, the table being pivotally mounted upon the holder and having its engaging surface inclined to the engaging surface of the abutment, means for normally maintaining the table in position to dispose the engaging surfaces at an angle different from that between the tread and the heel-seat-end surfaces of a heel to be clamped, and means for limiting the angular movement of the table to one in which the angle between the engaging surfaces is substantially that of the angle between the engaged surfaces.
102. In a machine for operating upon shoe-heels, a tool, a holder traveling to present a heel to the tool, said holder having a heel-clamping member variable in its angular position, means past which the holder travels for limiting the angular movement of the clamping member, and

means arranged to vary the position of the limiting means.

103. In a machine for operating upon shoe-heels, a tool, a holder traveling through a loading position and through an operating position, said holder having a heel-clamping member variable in its angular position, and means effective throughout the loading travel of the holder for limiting the angular movement of the clamping member.

104. In a machine for burnishing the top-lifts of heels, a movable burnishing tool, a rotatable turret, a series of heel-holders mounted upon the turret and each having a pivoted table free to tilt during the application of a heel by the operator, and a stop member into engagement with which a portion of the table may tilt during its travel and upon such application of a heel.

105. In a machine for burnishing the top-lifts of heels, a movable burnishing tool, a rotatable turret, a series of heel-holders mounted upon the turret and each having a pivoted table, means carried by each holder to limit the tilting movement of the table, and means common to the holders with which the limiting means contacts.

106. In a machine for burnishing the top-lifts of heels, a movable burnishing tool, a rotatable turret, a series of heel-holders mounted upon the turret and each having a pivoted table, means adjustable in position upon each holder to variably limit the tilting movement of the table, and a stop member into engagement with which a portion of the table may tilt during its travel.

107. In a machine for burnishing the top-lifts of heels, a movable burnishing tool, a rotatable turret, a series of heel-holders mounted upon the turret and each having a pivoted table, a loading platform past which the holders travel, means arranged to vary the angular position of the platform, and a stop member limiting the tilting movement of the tables and movable under the influence of the platform.

108. In a machine for burnishing the top-lifts of heels, a movable burnishing tool, a rotatable turret, a series of heel-holders mounted upon the turret and each having a pivoted table, a loading platform past which the holders travel, means arranged to vary the angular position of the platform, a stop-bar contacting with the platform and into engagement with which the tables may tilt, and a spring for maintaining such contact.

109. In a machine for operating upon shoe-heels, a traveling heel-holder, a tool to which the holder presents heels, and ejecting means movable with and upon the holder and having a portion for contact with a heel in said holder and arranged to yield bodily on the ejecting means.

110. In a machine for operating upon shoe-heels, a traveling heel-holder, a tool to which the holder presents heels, and a lever fulcrumed upon the holder and having an arm pivotally supported upon the lever and a spring urging one extremity of the arm about its pivotal connection to the lever toward a heel in the holder.

111. In a machine for operating upon shoe-heels, a rotatable turret, a series of carriages movable upon the turret, a heel-holder mounted upon each carriage, a tool to which the holders successively present heels, a heel-ejecting member mounted upon each carriage, and a contact member into engagement with which the ejecting members are successively advanced by the rotation of the turret.

112. In a machine for operating upon shoe-heels, a rotatable turret, a series of heel-holders mounted upon the turret and each having opposite clamping members with connecting rods, and a heel-ejecting member fulcrumed upon one of the rods of each holder.

113. In a burnishing machine, a tool mounted to turn about an axis and provided with a peripheral burnishing surface having a constant contour longitudinally of said axis during an operation upon the work, and means arranged to vary the angle of such surface to the axis.

114. In a burnishing machine, a tool mounted to turn about an axis and comprising a circumferential series of separate rigid sections furnishing at their outer ends a peripheral burnishing surface, and means arranged to vary the angle of the burnishing ends of the sections to the axis considered longitudinally thereof.

115. In a burnishing machine, a tool mounted to turn about an axis and comprising a circumferential series of separate rigid sections furnishing at their outer ends a peripheral burnishing surface, and means acting simultaneously upon all the sections to vary the angles of their burnishing ends to the axis longitudinally thereof.

116. In a burnishing machine, a shaft, means for turning said shaft, a support carried by the shaft, and a series of segments pivoted upon the support to swing longitudinally of the shaft and placed in close relation to one another, said segments furnishing at their outer ends a substantially continuous burnishing surface.

117. In a burnishing machine, a shaft, means for turning said shaft, a support carried by the shaft, a series of segments pivoted upon the support and placed in close relation to one another, said segments furnishing at their outer ends a substantially continuous burnishing surface, and means arranged to fix the segments in different positions on the support.

118. In a burnishing machine, a shaft, means for turning said shaft, a support carried by the shaft, a series of segments pivoted upon the support and placed in close relation to one another, said segments furnishing at their outer ends a substantially continuous burnishing surface, and means arranged to tilt the segments upon the support thus varying the angles of their burnishing surfaces to the axis of the shaft.

119. In a burnishing machine, a rotatable shaft, means for turning said shaft, a support carried by the shaft, a series of burnishing segments pivoted upon the support, and an adjusting member engaging each of the segments at the opposite side of its pivotal point from the axis of rotation.

120. In a burnishing machine, a shaft, means for turning said shaft, a support carried by the shaft, a series of burnishing segments pivoted upon the support, and adjusting members engaging the segments at opposite sides of the pivotal points.

121. In a burnishing machine, a shaft, means for turning said shaft, a support carried by the shaft, a series of burnishing segments pivoted upon the support, adjusting members engaging the segments at opposite sides of the pivotal points, a spring acting to force one of the members toward the segments, and manually operable means for adjusting the other member along the shaft.

122. In a burnishing machine, a shaft, means for turning the shaft, a plate secured to the shaft and having a circular rib, burnishing sections pivoted upon the rib, and a member turning with

and movable longitudinally of the shaft and engaging the sections at the side opposite the plate.

123. In a burnishing machine, a shaft, means for turning the shaft, a plate secured to the shaft 5 and having a circular rib, burnishing sections pivoted upon the rib, and two members turning with and movable longitudinally of the shaft, one of said members being provided with a circular rib engaging the sections at the inner side of the 10 plate-rib and the other member having a circular rib engaging the sections at the outer side of the plate-rib.

124. In a burnishing machine, a shaft, means for turning the shaft, a plate secured to the shaft 15 and having a circular rib, burnishing sections pivoted upon the rib, two members turning with and movable longitudinally of the shaft, one of said members being provided with a circular rib engaging the sections of the inner side of the 20 plate-rib and the other member having a circular rib engaging the sections at the outer side of the plate-rib, a spring surrounding the shaft and urging one member toward the sections, and a hand-wheel acting to vary the position of the other member.

125. In a burnishing machine, a shaft, means for turning the shaft, a plate secured to the shaft and having a hub extending along said shaft, burnishing sections movable upon the plate, and 30 two adjusting members splined to the hub and engaging the sections.

126. In a burnishing machine, a shaft, means for turning the shaft, a plate secured to the shaft and having a hub extending along said shaft, 35 burnishing sections movable upon the plate, two adjusting members splined to the hub and engaging the sections, a spring surrounding the hub and acting upon one member, and a hand-wheel threaded upon the hub and contacting with the 40 other member.

127. In a burnishing machine, a shaft, means for turning the shaft, a plate secured to the shaft, and a circumferential series of burnishing members mounted upon the plate and closely placed 45 with relation to one another in a series, the plate having means for pivotally supporting the members to swing longitudinally of the shaft and means for preventing their circumferential displacement.

128. In a burnishing machine, a movable plate, a circular series of burnishing members mounted upon the plate, and a circular electrical heating unit carried by the plate at the opposite side from the burnishing members.

129. In a burnishing machine, a movable plate having a recess, and an electrical heating unit situated in the recess, a cover-plate for the recess, and a series of burnishing members movable upon the cover-plate.

130. In a burnishing machine, a tubular shaft, means for turning the shaft, a burnishing tool carried by the shaft, a heating device mounted upon the tool, means arranged to vary the longitudinal position of the shaft, a current-delivering device carried by the shaft and movable therewith, and conductors extending through the shaft and joining the delivering device to the heating device.

131. In a burnishing machine, a tubular shaft, 70 means for turning the shaft, a burnishing tool carried by the shaft, a heating device mounted upon the tool, means arranged to vary the longitudinal position of the shaft, a casing surrounding the shaft and movable longitudinally therewith, collector-rings secured to the shaft, brushes

carried by the casing and contacting with the rings, flexible conductors entering the casing, and conductors connecting the collector-rings to the heating device and passing through the shaft.

132. In a burnishing machine, a tubular shaft, 5 means for turning the shaft, a burnishing tool carried by the shaft, a heating device mounted upon the tool, a member supporting the shaft, means arranged to move the member to vary the longitudinal position of the shaft, brushes mounted upon the member, collector-rings secured to the shaft and with which the brushes contact, flexible conductors joined to the brushes, and conductors connecting the collector-rings to the heating device and passing through the shaft. 10

133. In a machine for operating upon heels, a movable tool, an adjustable heel-holder movable in co-operation with the tool, a gage by which the correct adjustment of the holder for different heels may be determined, and means arranged to 20 vary the position of the tool to correspond to the adjustment of the holder.

134. In a machine for operating upon heels, a movable tool, a series of adjustable heel-holders traveling in co-operation with the tool, and a 25 gage into co-operation with which each holder may be moved for adjustment.

135. In a machine for operating upon heels, a movable tool, a series of adjustable heel-holders traveling in co-operation with the tool, a gage 30 into co-operation with which each holder may be moved for adjustment, and means arranged to vary the position of the tool to correspond to that of the holders.

136. In a machine for operating upon shoe-heels, a frame, a tool movable upon the frame, a turret rotatable upon the frame, heel-holders mounted upon the turret for co-operation with the tool, and a gage movable upon the frame from an inactive position removed from the turret to an active position adjacent to the path of the holders. 35

137. In a machine for operating upon shoe-heels, a frame, a tool movable upon the frame, a turret rotatable upon the frame, heel-holders 45 mounted upon the turret for co-operation with the tool, each holder having opposite clamping members for contact with a heel, means arranged to adjust the relation of one clamping member of each holder to the other, and a gage variable 50 in position upon the frame in the direction of adjustment of the clamping members and being movable into and out of gaging relation to the adjustable clamping members.

138. In a machine for operating upon shoe-heels, a frame, a tool movable upon the frame, a turret rotatable upon the frame, heel-holders mounted upon the turret for co-operation with the tool, each holder having opposite clamping members for contact with a heel, means arranged 60 to adjust the relation of one clamping member of each holder to the other, a standard rising from the frame adjacent to the turret, a gage variable in position vertically upon the standard and arranged to turn about the standard between an inactive position removed from the holders into gaging relation to the adjustable clamping members. 65

139. In a machine for operating upon shoe-heels, a frame, a turret having heel-holders and rotatable in the frame, a shaft arranged to turn at the axis of the turret, a tool carried by the shaft for co-operation with the heel-holders, and means arranged to vary the position of the tool longitudinally of the axis. 70

140. In a machine for operating upon shoe-heels, a frame, a turret having heel-holders and rotatable in the frame, a shaft arranged to turn at the axis of the turret, a tool carried by the shaft for co-operation with the heel-holders, a member held against movement upon the shaft longitudinally thereof and in which the shaft turns, and means arranged to move said member. 5
141. In a machine for operating upon shoe-heels, a frame, a turret having heel-holders and rotatable in the frame about a vertical axis, a shaft arranged to turn at the axis of the turret, a tool carried by the shaft for co-operation with the heel-holders, a yoke guided in the frame for vertical movement and having a threaded opening and an opening in which the shaft turns, collars secured to the shaft at opposite sides of the yoke, a screw rotatable in the frame and passing through the threaded opening, and connections 10 by which the screw may be rotated. 15
142. In a machine for operating upon shoe-heels, a tool, a holder traveling to present a contained heel to the tool, a heel-support extending along the path of the holder and from different points upon which a heel may be advanced into said holder during the travel thereof past the support, and a member movable upon the support during the travel of the holder to position the heel for delivery to said holder. 20
143. In a machine for operating upon shoe-heels, a tool, a holder traveling continuously in the operation of the machine to present a contained heel to the tool, a heel-support extending along the path of the holder, said support being arranged to direct a heel moved over it by the operator into the holder, and a member movable upon the support under the power of the machine during the travel of the holder to position the heel for delivery to said holder. 30
144. In a machine for operating upon shoe-heels, a tool, a holder traveling continuously in the operation of the machine to present a contained heel to the tool, a heel-support extending along the path of the holder, said support being arranged to direct a heel moved over it by the operator into the holder, and a member movable upon the support in timed relation to the travel of the holder to position the heel for delivery to said holder. 40
145. In a machine for operating upon shoe-heels, a tool, a holder provided with clamping means and traveling to present a clamped heel to the tool, a heel-support adjacent to the path of the holder, a member movable upon the support in timed relation to the travel of the holder to position the heel upon the support for delivery to said holder, and means for returning the member to its normal location. 50
146. In a machine for operating upon shoe-heels, a tool, a holder traveling continuously in the operation of the machine to present a contained heel to the tool, a heel-support extending along the path of the holder, said support being arranged to direct a heel moved over it by the operator into the holder, a member movable upon the support during the travel of the holder to position the heel for delivery to said holder, and means arranged to vary the normal angular relation of the member to the path of the holder. 60
147. In a machine for operating upon shoe-heels, a tool, a holder traveling continuously in the operation of the machine to present a contained heel to the tool, a heel-support extending along the path of the holder, and a heel- 70
- positioning and advancing member movable upon the support in transverse registration with the holder as it travels. 75
148. In a machine for operating upon shoe-heels, a tool, a holder traveling continuously in the operation of the machine to present a contained heel to the tool, a heel-support extending along the path of the holder, and a heel-positioning and advancing member movable upon the support and having a projection extending into the path of an element traveling with the holder. 80
149. In a machine for operating upon shoe-heels, a tool, a holder traveling continuously in the operation of the machine to present a contained heel to the tool, a heel-support extending along the path of the holder, a heel-positioning and advancing member movable upon the support and having a projection extending into the path of an element traveling with the holder, and means arranged to fix the projection in different relations to the path of the holder. 85
150. In a machine for operating upon heels, a movable tool, a series of heel-holders traveling in co-operation with the tool, a heel-support extending along the path of the holders, and a heel-positioning and advancing member movable upon the support along the path of the holders and in a direction inclined inwardly toward said path. 90
151. In a machine for operating upon heels, a movable tool, a series of heel-holders traveling in co-operation with the tool, a heel-support adjacent to the path of the holders, and a heel-positioning and advancing member movable upon the support and receiving movement imparted to it by each holder as said holder passes the support. 95
152. In a machine for operating upon heels, a movable tool, a series of heel-holders traveling in co-operation with the tool, a heel-support adjacent to the path of the holders, a heel-positioning and advancing member movable upon the support and receiving movement upon the passage of each holder, and a spring exerting its force to move the positioning and advancing member in the opposite direction. 100
153. In a machine for operating upon shoe-heels, a tool, a heel-holder traveling to present heels to the tool, a loading platform extending along the path of the holder and arranged to receive heels and permit their advance by the operator into the holder, a slide movable upon the platform, and a positioning member carried by the slide and arranged to guide heels moved along it toward the holder by the operator. 105
154. In a machine for operating upon shoe-heels, a tool, a heel-holder traveling to present heels to the tool, a loading platform extending along the path of the holder, a slide guided upon the platform to move in a direction inclined to the holder-path, thereby following the holder in its travel and approaching its path, and a heel-positioning member carried by the slide and having a heel-contact-surface extending toward the path of the holder. 110
155. In a machine for operating upon shoe-heels, a tool, a heel-holder traveling to present heels to the tool, a loading platform extending along the path of the holder, a slide guided upon the platform to move both toward the holder and in the direction of its travel, a heel-positioning member carried by the slide and having a heel-contact-surface extending toward the path 115

of the holder, and means arranged to vary the angular relation of the member upon the slide.

156. In a machine for operating upon shoe-heels, a tool, a rotatable turret, a series of heel-holders revolved by the turret in co-operation with the tool, a platform past the inner edge of which the holders are successively advanced, there being a slot in the platform extending transversely thereof but inclined inwardly toward the turret, a slide guided in the slot, and a heel-contact member secured to the slide.

157. In a machine for operating upon shoe-heels, a tool, a rotatable turret, a series of heel-holders revolved by the turret in co-operation with the tool, a platform past the inner edge of which the holders are successively advanced, there being a slot in the platform extending transversely thereof but inclined inwardly toward the turret, a slide guided in the slot, there being a projection from the turret for each holder and a projection from the slide receiving contact of the turret-projections to successively advance the slide in the direction of travel of the holders, and a heel-contact member secured to the slide.

158. In a machine for operating upon shoe-heels, a tool, a rotatable turret, a series of heel-holders revolved by the turret in co-operation with the tool, a platform past the inner edge of which the holders are successively advanced, there being a slot in the platform extending transversely thereof but inclined inwardly toward the turret, a slide guided in the slot, a heel-contact member secured to the slide, means carried by the turret for moving the slide in one direction, and a spring connecting the slide to the platform to move it in the opposite direction.

159. In a machine for operating upon shoe-heels, a tool, a rotatable turret, a series of heel-holders revolved by the turret in co-operation with the tool, a platform past the inner edge of which the holders are successively advanced, there being a slot in the platform extending transversely thereof but inclined inwardly toward the turret, a slide guided in the slot, there being a projection from the turret for each holder and a projection from the slide receiving contact of the turret-projections to successively advance the slide in the direction of travel of the holders, a heel-contact member secured to the slide, and means arranged to secure the slide-projection in different positions toward and from the turret-projections.

160. In a machine for operating upon shoe-heels, a tool, a rotatable turret, a series of heel-holders revolved by the turret in co-operation with the tool, a platform past the inner edge of which the holders are successively advanced, there being a slot in the platform extending transversely thereof but inclined inwardly toward the turret, a slide guided in the slot, a heel-contact member pivoted at one extremity upon the slide, and means for fixing the member in different angular positions about its pivot.

161. In a machine for operating upon shoe-heels, a movable tool, a heel-holder traveling in co-operation with the tool and provided with a heel-locating member variable in position to correspond to different heels, and a gage normally fixed against movement relatively to the travel of the heel-holder and co-operating with the heel-locating member to determine its position.

162. In a machine for operating upon shoe-heels, a movable tool, a heel-holder traveling in

co-operation with the tool and provided with a heel-locating member variable in position to correspond to different heels, and a gage fixed against movement in the direction of travel of the holder and co-operating with the heel-locating member to determine its position, said gage being arranged for adjustment toward and from the path of the holder.

163. In a machine for operating upon shoe-heels, a movable tool, a series of heel-holders traveling in co-operation with the tool and each provided with a heel-locating member variable in position to correspond to different heels, and a gage into co-operation with which each heel-locating member may be moved to determine its position.

164. In a machine for operating upon shoe-heels, a movable tool, a series of heel-holders traveling in co-operation with the tool and each provided with a heel-locating member variable in position to correspond to different heels, a mounting normally fixed against movement, and a gage pivoted upon a mounting and movable thereon into and out of co-operation with each heel-locating member.

165. In a machine for operating upon shoe-heels, a movable tool, a series of heel-holders traveling in co-operation with the tool and each provided with a heel-locating member variable in position to correspond to different heels, a mounting normally fixed against movement, means arranged to fix the mounting in different positions, toward and from the path of the holders, and a gage carried by the mounting for co-operation with each heel-locating member.

166. In a machine for burnishing the top-lifts of heels, a rotatable turret, a plurality of heel-holders carried by the turret and each provided with a breast-bar, means arranged to vary the location of each bar upon its holder, a loading support past which the holders travel in the rotation of the turret, and a gage carried by the support for co-operation with the breast-bars.

167. In a machine for burnishing the top-lifts of heels, a rotatable turret, a plurality of heel-holders carried by the turret and each provided with a breast-bar, means arranged to vary the location of each bar upon its holder, a loading support past which the holders travel in the rotation of the turret, a mounting carried by the support, means arranged to fix the mounting in different positions toward and from the turret, and a gage pivoted upon the mounting for movement into and out of co-operation with the breast-bar of any one of the holders.

168. In a machine for operating upon shoe-heels, a rotatable turret, a tool-shaft mounted to turn at the axis of the turret, means for rotating the shaft, a generally circular tool carried by the shaft, and plural heel-holders supported upon the turret and all co-operating with the tool.

169. In a machine for operating upon shoe-heels, a rotatable turret, a tool-shaft mounted to turn at the axis of the turret, means for oscillating the shaft, a generally circular tool carried by the shaft, and plural heel-holders supported upon the turret and all co-operating with the tool.

170. In a machine for operating upon shoe-heels, a rotatable turret, a tool-shaft mounted to turn at the axis of the turret, a rotatable driving shaft extending transversely of the tool-shaft, gearing communicating the rotation of the driving shaft to the tool-shaft, a generally

circular tool carried by the shaft, and plural heel-holders supported upon the turret and all co-operating with the tool.

171. In a machine for operating upon shoe-
5 heels, a rotatable turret, a tool-shaft mounted
to turn at the axis of the turret, a rotatable driv-
ing shaft extending transversely of the tool-

shaft, a device joined to the driving shaft and
converting its rotation into oscillation, connec-
tions to said device for oscillating the tool-shaft,
a circular tool carried by the shaft, and plural
heel-holders supported upon the turret and all 5
co-operating with the tool.

CHARLES G. BROSTROM.
